DEFENSIVE PUBLICATION

UNITED STATES PATENT OFFICE

Published at the request of the applicant or owner in accordance with the Notice of Dec. 16, 1969, 869 O.G. 687. T abstracts of Defensive Publication applications are identified by distinctly numbered series and are arranged chronological in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

No Drawing. 10 Pages Specification

Photographic elements useful as positive-working planographic printing plates and having a hydrophobic, ink-receptive support coated with a light-sensitive hydrophilic layer including a diazo resin and a hydrophilic polymer can be prepared with low polymer concentrations by employing a polyvinylacetal of 2,4-disulfobenzaldehyde as the hydrophilic polymer.
